UNITED STATES PATENT OFFICE.

VICTOR G. MUNSON, OF WHITEHALL, MICHIGAN.

ROTARY PUMP.

1,128,999.

Specification of Letters Patent. Patented Feb. 16, 1915.

Application filed June 28, 1913. Serial No. 776,341.

To all whom it may concern:

Be it known that I, VICTOR G. MUNSON, a citizen of the United States, residing at Whitehall, in the county of Muskegon and State of Michigan, have invented certain new and useful Improvements in Rotary Pumps, of which the following is a specification.

This invention relates to fluid transmitting pumps of the rotary type, and has for an object the provision of a rotary pump for efficiently pumping water and like liquids.

Another object of this invention is the provision of an improved valve mechanism which is automatically operated by the operation of a pump plunger and which prevents any fluid which is drawn in the pump casing from receding into the inlet of the pump.

A still further object of this invention is the provision of a pump plunger which is provided with means for automatically taking up any wear caused by the continuous operation or rotation of the plunger.

With the foregoing and other objects in view, this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in which,

Figure 1 is a vertical sectional view through the improved pump; Fig. 2 is a side elevation of the pump showing one side of the outer casing removed; Fig. 3 is a cross sectional view through the pump; Figs. 4 and 5 are detailed side elevations of parts of the pump; Fig. 6 is a detailed perspective view of the pump plunger; and Fig. 7 is a detailed perspective view of the improved valve for preventing the backward action of the water which is drawn into the pump casing.

Referring more particularly to the drawings, the numeral 1 designates one side of the outer casing of the pump and has a flange 2 formed integrally therewith and extending inwardly from the inner surface of the side 1. The side 1 of the casing of

the pump is circular in shape as is clearly shown in Figs. 1 and 2 of the drawings.

The side 1 has a bearing 3 formed thereupon in which is rotatably mounted a shaft 4. The shaft 4 has a shoulder 5 formed thereupon and the reduced portion 6 of the shaft which extends beyond the shoulder 5 has external screw threads formed thereupon adjacent the shoulder 5. The external screw threads formed upon the reduced portion of the shaft 4 are engaged by a nut 7 which is seated in a recess 8 centrally located in the washer 9 which is constructed of leather or other suitable material. The washer 9 is held in place and against the edge of the flange 2 by means of a plate 10 which is secured on the flange 2 by means of bolts 11 which are inserted in screw threaded apertures 12 formed in the flange 2.

The shaft 6 has connected to its outer end any suitable means (not shown) for transmitting power thereto such as a crank handle, pulley or the like.

A plate 15 is mounted upon the reduced portion 6 of the shaft 4, abutting the shoulder 5, and rotates in unison with the shaft 4. This plate 15 is provided with a cut out portion 16, formed therein, which receives the main body portion 17 of the pump plunger 18. The plunger 18 has a reduced portion 19 formed integrally therewith and extending outwardly from one end thereof. The reduced portion 19 gradually tapers inwardly as it extends away from the body portion 17 of the plunger 18 and terminates in a point 20. The reduced portion 19 has a roller 21 rotatably mounted upon its upper surface, the purpose of which will be hereinafter more fully described.

Seated within a recess 22 formed in the body portion 17 of the plunger 18 is a plate 23 which has an expanding coil spring 24, which is seated within a recess 25 formed in the plunger 18 abutting its inner surface and pressing the plate 23 outwardly so as to engage the inner surface of the flange 2 during the operation of the plunger 18. This plate 23 serves a purpose identical with the piston rings of an engine in that it absorbs the wear occasioned by the continuous operation of the plunger 18.

By seating the body portion 17 of the plunger 18 within the recess 16 formed in the plate 15, the plunger will be caused to

rotate synchronously with the plate 15 and as the plate 15 is rigidly connected to the shaft 4, the former will rotate when rotary motion is imparted to the shaft 4 by the means heretofore set forth. In this manner the operation of the plunger 18 may be started.

The flange 2 has two openings 30 and 31 formed therein each of which receives a screw threaded portion of the pipes 32 and 33 respectively. The pipe 32, which is seated in the opening 30 has a second pipe 34 connected thereto in any suitable manner. The pipe 34 has its end 35, which is connected to the pipe 32, enlarged and a ball 36 is seated therein. The pipes 34 and 32 and the opening 30 form an inlet for the interior of the casing of the pump and the pipe 34 is connected to any suitable source of water or other liquid supply. The ball 36 is of greater diameter than the interior of the pipe 32 and the latter has its end 37 which is seated within the enlarged portion 35 of the pipe 34, shaped so as to form a seat for the ball 36 and prevent the same from passing into the interior of the casing. The end 37 of the pipe 32 is also shaped so as to allow water or other fluid to pass therefrom and into the interior of the casing of the pump when the ball 36 is in engagement therewith.

The opening 31 and the pipe 33 form an outlet for the fluid which is drawn into the interior of the casing of the pump through the inlet opening.

A circular shaped member 38 is mounted within the pump casing and is securely and rigidly connected to the side by means of bolts 39. The shaft 4 is rotatably mounted in an opening 40 which extends through the member 38.

The member 38 has a cut out portion 41 formed in its lower side which receives the tongue 42 of the valve member 43. The tongue 42 is pivotally connected to the member 38 by means of a pin 44. The lower end 45 of the valve member 43 is shaped so as to fit snugly against the inner surface of the flange 2 and form a fluid tight joint therewith. The outer lower edge 46 of the tongue 42 is shaped so as to conform to the shape of the upper edge 47 of the reduced portion 19 of the plunger 18 and is engaged by the roller 21 during a predetermined period in the operation of the plunger 18. When the roller 21 engages the surface 46 of the tongue 42 it forces the same upwardly within the recess 41 formed in the member 38 and forces the valve member 43 upwardly in a recess 48 which is formed within the member 38 and against the tension of a coil spring 49 which is mounted within the recess 48.

A recess 50 communicates with a recess 48 and has a coil spring 51 mounted therein.

The coil springs 49 and 51 force the valve member 43 outwardly out of the recess 48 and into its normal position as is shown in Fig. 1 of the drawings, after the plunger 18 has passed beyond the outer edge of the opening 48 during its stroke. A small opening 52 communicates with the upper and inner end of the recess 50 and extends entirely through the member 38 forming an outlet for any air, water or the like which might be contained within the recesses 49 and 50.

The valve member 43 forms means for preventing the water or other fluid which is drawn into the interior of the pump casing from receding into the pipe 32 and causes the entire amount of fluid drawn into the casing, upon each stroke of the piston 18, to be forced outwardly through the pipe 33.

A peripheral chamber is formed in the casing of the pump about the outer surface of the member 38 and the plunger 18 operates within this chamber.

The suction generated by the operation of the plunger 18 within the peripheral chamber formed in the casing draws water or other liquid into the peripheral chamber through the inlet and as the plunger 18 fits snugly within the peripheral chamber within the interior of the casing and about the outer edge of the member 38 the fluid is forced outwardly through the pipe 33 by the shoulder 54 of the body portion 17 of the plunger 18.

In practical fields certain minor features of construction, combination and arrangement of parts may necessitate alterations to which the patentee is entitled provided such alterations are comprehended within the scope of what is claimed.

What is claimed is:—

1. A rotary pump comprising a casing having a peripheral chamber therein, a plunger operable within said peripheral chamber, means for imparting motion to said plunger from any suitable power source, inlet and outlet ports for said chamber, a stationary member mounted within the case to form the inner wall of said peripheral chamber, and means for preventing any liquid which is drawn into said peripheral chamber through said inlet from receding into the inlet.

2. A rotary pump comprising a casing having a peripheral chamber therein, a plunger operable within said peripheral chamber, means for imparting motion to said plunger from any suitable power source, a member rigidly connected within the casing to have the plunger carried therearound in its path of movement, inlet and outlet ports for said chamber, means for preventing any liquid which is drawn into said peripheral chamber through said inlet from receding into the inlet and means car-

ried by said plunger for absorbing the wear occasioned by the continuous operation of the plunger.

3. A rotary pump comprising a casing having a peripheral chamber therein, a plunger operable within said peripheral chamber, means for imparting motion to said plunger from any suitable power source, inlet and outlet ports for said chamber, a member rigidly connected to one side of said casing and extending into the interior of the same and means carried by said member for preventing fluid which is drawn into said peripheral chamber through said inlet from receding into said inlet.

4. A rotary pump comprising a casing having a peripheral chamber therein, a plunger operable within said peripheral chamber, means for imparting motion to said plunger from any suitable power source, inlet and outlet ports for said chamber, a member rigidly connected to one side of said casing and extending into the interior of the same, a valve member pivotally connected to said member said valve member forming means whereby any fluid drawn into said peripheral chamber through said inlet will be prevented from receding into said inlet and means carried by said plunger for moving said valve member out of the path of said plunger.

5. A rotary pump comprising a casing having a peripheral chamber therein, a plunger operable within said peripheral chamber, means for imparting motion to said plunger from any suitable power source, inlet and outlet ports for said chamber, a member rigidly connected to one side of said casing and extending into the interior of the same, a valve member pivotally connected to said member said valve member forming means whereby any fluid drawn into said peripheral chamber through said inlet will be prevented from receding into said inlet, means carried by said plunger for moving said valve member out of the path of said plunger and means carried by said plunger for reducing the friction generated by the engagement of said last named means and said valve member.

6. A rotary pump comprising a casing, a member rigidly connected in the center of said casing to provide a peripheral chamber therearound, a plunger received in said peripheral chamber, means to transmit motion to said plunger to cause travel thereof through the chamber, inlet and outlet ports for said chamber, a valve carried by said rigidly connected member, and all of said parts so arranged that the movement of the

plunger through the chamber causes liquid to be drawn thereinto through the inlet and discharged through the outlet.

7. A rotary pump comprising a casing, 65 a member rigidly connected to one side of said casing and extended into the interior thereof to provide a peripheral chamber, a plunger operable within said peripheral chamber to travel throughout the extent 70 thereof, inlet and outlet ports for said chamber, and means carried by said stationary member to cause liquid to be taken through the inlet and discharged from the peripheral chamber through the outlet port.

8. A rotary pump comprising a casing having a circular interior opening, a circular member rigidly connected with one side of said casing to extend thereinto and to form the opening of the casing into a peripheral chamber, a plunger operable to have movement throughout the extent of the peripheral chamber, a valve member carried by said rigid member to normally close the peripheral chamber at a point adjacent the disposition thereof, inlet and exhaust ports for said chamber, and said plunger so formed and mounted that the movement thereof through the chamber causes liquid to be drawn through the inlet 80 and discharged through the outlet and said valve is caused to be operated in the proper intervals.

9. A rotary pump comprising a casing made circular in its internal opening, a circular member rigidly connected with one side of said casing to extend thereinto and to form the opening of the casing into a peripheral chamber, a valve socket provided in said rigid member, a valve pivotally connected in said socket to be capable of movement thereinto to be entirely without the peripheral chamber, means to normally hold the valve in a position to obstruct the peripheral chamber at a point adjacent the 100 mounting thereof, a plunger operable within said peripheral chamber, means for imparting motion to said plunger from any suitable power source, inlet and outlet ports for said chamber, and all of said parts so 110 arranged that liquid is taken into the chamber through the inlet and is discharged therefrom through the outlet and the several parts are operated in the proper interval.

In testimony whereof I affix my signature in presence of two witnesses.
